MAGNETRON DEVICE

Benjamin V. Valles, San Jose, Calif., assignor to Litton Precision Products, Inc., San Carlos, Calif., a corporation of Delaware

Filed Feb. 16, 1968, Ser. No. 10,610

Term of patent 14 years

(Cl. D26—8)

FIG. 1 is a perspective view of a magnetron device showing my new design;

FIG. 2 is a side elevation thereof; the opposite side is a mirror image of the side shown; and

FIG. 3 is a front elevation thereof; the undisclosed rear side is a mirror image of the front side shown.

I claim:

The ornamental design for a magnetron device, substantially as shown as described.
